UNITED STATES PATENT OFFICE

106,663

DESIGN FOR FRONT END COVER FOR A VACUUM CLEANER CASING OR SIMILAR ARTICLE

Lurelle Guild, Darien, Conn., assignor, by mesne
assignments, to Electrolux Corporation, Dover,
Del., a corporation of Delaware

Original application March 25, 1937, Serial No.
D-68,404. Divided and this application Sep-
tember 8, 1937, Serial No. D-71,508

Term of patent 14 years

To all whom it may concern:

Be it known that I, Lurelle Guild, a citizen of
the United States of America, residing in Darien,
Connecticut, have invented a new, original, and
ornamental Design for Front End Cover for a
Vacuum Cleaner Casing or Similar Article, of
which the following is a specification, reference
being had to the accompanying drawing, forming
part thereof.

This application is a division of my co-pending
application Serial No. D-68,404, filed March 25,
1937.

Fig. 1 is an end view of the front end cover,
showing my new design.

Fig. 2 is a side view of the front end cover, and
Fig. 3 is a perspective view of the front end cover.

I claim:

The ornamental design for front end cover for
a vacuum cleaner casing or similar article, as
shown.

LURELLE GUILD.
